CLAIM

The ornamental design for a portion for oral care implement, as shown and described.

DESCRIPTION

FIG. 1 is a front right perspective view of a portion for an oral care implement according to the new design, the front left perspective view being a mirror image thereof;

FIG. 2 is a rear left perspective view thereof, the rear right perspective view being a mirror image thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

In the drawings, the broken lines of equal length shown in the drawings illustrate portions of the oral care implement that form no part of the claimed design. The broken lines of unequal length represent the boundaries of the claimed design and form no part of the claimed design.
